CLAIM

I claim the ornamental design for an African mask fireplace,
as shown and described.

DESCRIPTION

FIG. 1 is a perspective view to an African mask fireplace using African symbols and culture as indicated and shown in my new design;

FIG. 2 is a front view thereof;

FIG. 3 is a top view looking down thereof;

FIG. 4 is a left side view thereof; and,

FIG. 5 is a right side view thereof.
